PAGE 2

FIG-3

FIG-4

FIG-6

FIGURE 1 is a perspective view of a heater convector casing unit showing our new design with the partial outline of a room and a blower powered unit shown in dotted lines for illustrative purposes only;

FIGURE 2 is a fragmentary perspective view drawn at enlarged scale showing the left end terminal portion of the heater convector casing unit of FIGURE 1;

FIGURE 3 is a front elevational view of the portion illustrated in FIGURE 2;

FIGURE 4 is a plan view thereof;

FIGURE 5 is a left end elevational view thereof and;

FIGURE 6 is a perspective sectional view indicated by line 6-6 on FIGURE 2 and drawn at still larger scale.

We claim:
The ornamental design for a heater convector casing unit, substantially as shown and described.
